UNITED STATES PATENT OFFICE.

JOHN CARLSON AND MATTHIAS CARLSON, OF MACE, IDAHO.

LACING DEVICE.

1,282,539.

Specification of Letters Patent. Patented Oct. 22, 1918.

Application filed June 16, 1916. Serial No. 104,022.

To all whom it may concern:

Be it known that we, JOHN CARLSON and MATTHIAS CARLSON, subjects of the Czar of Russia, residing at Mace, in the county of 5 Shoshone and State of Idaho, have invented certain new and useful Improvements in Lacing Devices; and we do hereby declare the following to be a full, clear, and exact description of the invention, such as will 10 enable others skilled in the art to which it appertains to make and use the same.

This invention relates to improvements in lacing devices for shoes, and has for its object to provide a device of this character 15 embodying a roller supporting the shoe lace or string so as to reduce the resistance to the movement of the lace to the minimum.

Another object is the provision of a supporting frame for the friction reducing 20 roller which may be inexpensively stamped from sheet metal and effectively anchored in position on the flaps or meeting edges of the shoe.

With these and other objects in view, the 25 invention consists in the novel construction, combination and arrangement of parts as will be hereinafter specifically described, claimed and illustrated in the accompanying drawing, in which:

30 Figure 1 represents a perspective view of a shoe, partly broken away, illustrating the improved lacing devices applied thereto,

Fig. 2 represents a perspective view of one of the lacing devices removed, and

35 Fig. 3 represents a perspective view of the modified type of the lacing device.

Referring to the drawing in detail, wherein similar reference numerals designate corresponding parts throughout the several 40 views, the numeral 5 indicates a shoe having the opposed flaps or free edges 6 in which are anchored strips 7, constructed of relatively thin and narrow spring metal.

A row of lacing devices 8 is anchored in 45 each flap 6 of the shoe by one of the anchoring strips 7 and each lacing device includes a frame 9 constructed entirely of a single piece of sheet metal, bent centrally to define a U-shaped member 10 in which is secured a

pin 11, rotatably supporting a friction reducing roller 12 supporting the shoe lace or string 13. The inner end of the frame 9 is beveled or cutaway, as indicated at 14, to insure against the lace 13 coming in contact therewith and one side member of the U-shaped member 10 is offset, as indicated at 15, and extended substantially in line with the other side member of the U-shaped member. The last mentioned end of the U-shaped member, which is designated by the numeral 16, is turned back over the anchoring strip 7, as indicated at 17 to provide a closed loop which rigidly secures the lacing device thereto.

From the foregoing it is evident that the 65 shoe lace 13 may be readily drawn over the rollers 12 to draw the edges or flaps 6 of the shoe together, while the spring strips 7 permit the shoe to freely curve to comfortably fit the foot and angle of the wearer.

In the modification of the invention illustrated in Fig. 3 the numeral 18 indicates generally the lacing device constructed of a single piece of sheet metal and is bent centrally to define a U-shaped member 19, the 75 web portion 20 of which is curved from end to end for engagement with the shoe lace 13. This type of lacing device is secured to anchoring strips 7 in the same manner as the lacing device 9 and is particularly designed 80 for use in connection with low shoes on which only a comparatively few of the lacing devices are necessary to secure the shoe lace in position thereon.

What I claim is:

1. A lacing device comprising a frame including a substantially U-shaped lace-receiving member, a flexible anchoring strip, and a closed loop integrally connected with the U-shaped lace-receiving member rigidly securing the anchoring strip to the frame.

2. A lacing device comprising a frame including a substantially U-shaped lace-receiving member, a flexible anchoring strip, and a closed loop connected with one of the sides 95 of the U-shaped member rigidly securing the frame to the anchoring strip.

3. A lacing device comprising a frame in-

cluding a substantially U-shaped lace-receiving member having portions of the web and side members cutaway, a roller journaled between the side members of the U-shaped frame, a flexible anchoring strip, and a closed loop integrally connected with the U-shaped member receiving and securing the anchoring strip.

In testimony whereof we affix our signatures in presence of two witnesses.

JOHN CARLSON.
MATTHIAS CARLSON.
